CONTAINER

Samuel Rosen, Providence, R. I.

Application November 17, 1942, Serial No. 465,866

12 Claims. (Cl. 229—8)

This invention relates to a container made from cardboard or some similar material which may be used for displaying various articles, such for instance as confections, and the construction is particularly designed for a container which will have a curved shape, such for instance as a heart shape.

In the formation of containers of curved outline, such for instance as the shape of a heart, the side walls of the container which is curved has heretofore been rather expensive to construct and has been of a somewhat clumsy construction adaptable to hold only very light weight articles and in many instances the side walls have been formed separate from the bottom wall and attached thereto by cementing or the like.

One of the objects of this invention is to simplify the formation of a container having a curved shape, particularly a heart, to eliminate the necessity of utilizing two pieces of stock for the formation of the same.

Another object of this invention is to provide a container from a single piece of sheet stock in which the bottom walls and side walls which are folded therefrom may be of such a shape as to substantially reinforce the side walls.

Another object of this invention is to provide interlocking means not only between the ends of the meeting side walls but also between the side walls and the bottom wall while at the same time providing a reinforcement each with the other that a rigid construction may be obtained.

With these and other objects in view, the invention consists of certain novel features of construction, as will be more fully described and particularly pointed out in the appended claims.

In the accompanying drawings:

Fig. 1 is a top plan view of the container;

Fig. 2 is a bottom plan view of the container, illustrating in dot-and-dash lines a segment being attached to the side wall strips before being folded into final position;

Fig. 3 is a plan view of the blank cut out from sheet stock prior to the blank being folded into finished box shape and broken to show a fore-shortening of the segments;

Fig. 4 is a perspective view illustrating the blank as partially folded into box shape;

Fig. 5 is a perspective view illustrating a further step in the folding of the box into final shape;

Fig. 6 is a fragmental perspective view illustrating the point end of the box and looking at the under side thereof to illustrate the manner

of folding and securing the segments into position;

Fig. 7 is a perspective view of the box just prior to attachment of the last end wall into position;

Fig. 8 is a section on line 8—8 of Fig. 1; and

Fig. 9 is a section on line 9—9 of Fig. 1.

In proceeding with this invention the contour of the bottom wall is formed flat and then the side walls are attached along a short length of the bottom wall at a curved portion thereof to extend in opposite directions and of a length so that when folded up at right angles to the bottom wall they may follow the contour of the bottom wall and meet with the ends of a similar side wall. Interlocking means are then provided so that these meeting ends of the side walls may interlock one with the other and also lock with the bottom wall so as to maintain the side walls in upright position along the edge of the bottom wall and the following is a more detailed description of the construction by which the invention is accomplished.

With reference to the drawings, Fig. 3 illustrates a plan view of the blank as cut from sheet stock. It consists of a flat body section 10 having the contour 11 of heart shape which forms the bottom wall. Strips designated generally 12 and 13 and of the same piece of stock as the section 10 are attached as at 14 and 15 thereto along the curved outline thereof. These strips extend in opposite directions and are scored as at 16 and 17 to be folded upwardly at right angles to the section 10. Strips 12 and 13 are scored as at 16 and 17 to be folded upon themselves as shown at 18 in Fig. 4 and provide a double side wall designated 19 and 20 also illustrated in Fig. 4. These side walls when bent at right angles to the bottom section 10 may be bent or curved to follow the contour 11 of the bottom section 10 and will be provided of such a length that these side walls will meet at the point 21 of the bottom section, and also meet at the apex 22 of the indented portion of the heart opposite this point 21.

The strip 12 is provided with a tab 23 which extends beyond the wall 19 and fits into or between the folds of the double wall 20 so as to assist in retaining these walls in meeting relation as shown in Fig. 1. This tab 23 is illustrated as about to be inserted between the folds of the side wall 20 in Fig. 7. Locking ears 24 and 25 are also provided on the strips 12 and 13 which extend from the walls 19 and 20 as shown in Fig. 4 to enter the slits 26 and 27 in the bottom section 10. The ears are provided with hooks

28 to be retained in the slits 26 and 27 after insertion therein in the manner shown in Figs. 5 and 7.

Flanges 29 and 30 are provided along the straight portion of the bottom section 10 extending from the point 21 thereof to be folded along score lines 31 and 32 upwardly at right angles to the bottom section 10 to interlock with and provide a reinforcement for the side walls when secured in position.

The side walls 19 and 20 of double construction from their point of attachment may be curved to extend along the straight edge contour of the heart and as these side walls open downwardly they are adapted to receive and do receive the flanges 29 and 30 which are folded upwardly from the bottom section 10. Flange 29 is slotted as at 33 and a tab 33' formed on the strip 13 extending beyond the side wall 20 extends into this slot 33 so as to hold the side wall locked in position at the apex. Side wall 19 also straddles the flange 29 and is held in position by such relation. A segment 34 is formed on the strip 13 and segment 35 on the strip 12. Segment 34 is scored as at 36 and folded along this score line to extend beneath and reinforce the bottom section 10. This portion is of a shape to just coincide with the shape of the bottom over the pointed end of the heart. Segment 35 which is scored at 37 is folded along its score line and is of a shape to just overlie the segment 34. A tab 38 is provided on the segment 35 to extend into slot 33 positioned along the score line 36 at a location to receive the tab 38.

After the box has been blanked out, scored and slotted as shown in Fig. 3 it is usually preferable in assembling the box to first fold up the flanges 29 and 30, then fold up the strip 13 and assemble the wall 20 thus folded up as illustrated in Figs. 4 and 5, then to fold up the strip 12 and assemble the wall 19 thus formed first at the bottom or point end as shown in Fig. 7 and lastly to tuck the tab 23 in between the plies of the wall 20 and then lock ear 24 into the slot 26.

After the box is formed complete as shown in Figs. 1 and 2 it will be readily observed that I have provided a very strong construction consisting of three plies of stock along the point end portion of the heart-shaped box and three ply construction of side wall along this same portion while a double ply side wall extends throughout the remainder of the box. The locking ears 24 and 25 are also sufficiently large so as to reinforce at the same time that they lock the side walls of the box at the apex of the indented portion of the heart shape while providing at this location a double ply of material.

I claim:

1. A box body comprising a flat bottom section of heart shape, opposite side walls of the same piece of material folded upwardly at the opposite sides of the curvature thereof and folded outwardly upon themselves to be of double thickness and extending to the point of the angle of the heart and to the apex of the indented portion thereof opposite said point, and cooperating means between said bottom section and side walls for locking the meeting ends of the side walls together and to the bottom wall.

2. A box body comprising a flat bottom section of heart shape having straight portions, opposite side walls of the same piece of material folded upwardly at the opposite sides of the curvature thereof and folded outwardly upon themselves

to be of double thickness and extending to the point of the angle of the heart and to the apex of the indented portion thereof opposite said point, and cooperating means between said bottom section and side walls for locking the meeting ends of the side walls together and to the bottom wall and a flange folded upwardly along the straight portion of the contour of the bottom section extending between the double thickness of said side wall.

3. A box body comprising a flat bottom section of heart shape having straight portions, opposite side walls of the same piece of material folded upwardly at the opposite sides of the curvature thereof and folded outwardly upon themselves to be of double thickness and extending to the point of the angle of the heart and to the apex of the indented portion thereof opposite said point, and cooperating means between said bottom section and side walls for locking the meeting ends of the side walls together and to the bottom wall and a flange folded upwardly along the straight portion of the contour of the bottom section extending between the double thickness of said side wall and a tab at the end of one of said side walls and a slot in the end portion of a flange interlocking with the other side wall to secure said wall in position.

4. A box body comprising a flat bottom section of heart shape, opposite side walls of the same piece of material folded upwardly at the opposite sides of the curvature thereof and extending to the point of the angle of the heart and to the apex of the indented portion thereof opposite said point, and cooperating means between said bottom section and side walls for locking the meeting ends of the side walls together and to the bottom wall and reinforcing bottom segments on the side wall strips folded one over the other beneath the bottom section and interlocking means to secure them in position.

5. A box body comprising a flat bottom section of heart shape, opposite side walls of the same piece of material folded upwardly at the opposite sides of the curvature thereof and extending to the point of the angle of the heart and to the apex of the indented portion thereof opposite said point, and cooperating means between said bottom section and side walls for locking the meeting ends of the side walls together and to the bottom wall and reinforcing bottom segments on the side wall strips folded beneath the bottom section, a tab on one of said segments and a slot at the junction of the other segment and the side wall from which it is folded to receive said tab.

6. A box body comprising a flat bottom section of heart shape, opposite side walls of the same piece of material folded upwardly at the opposite sides of the curvature thereof and extending to the point of the angle of the heart and to the apex of the indented portion thereof opposite said point, and cooperating means between said bottom section and side walls for locking the meeting ends of the side walls together and to the bottom wall, tabs at the ends of said side walls and slits in the bottom wall for receiving said tabs to assist in holding the side walls in position.

7. A box body comprising a flat bottom section of heart shape, opposite side walls of the same piece of material folded upwardly at the opposite sides of the curvature thereof and extending to the point of the angle of the heart and to the apex of the indented portion thereof opposite

said point, and cooperating means between said bottom section and side walls for locking the meeting ends of the side walls together and to the bottom wall, tabs at the ends of said side walls adjacent said apex and slits in the bottom wall for receiving said tabs to assist in holding the side wall in position.

8. A one-piece blank for a box body, comprising a bottom forming section of heart-shaped contour and opposite side wall forming strips each connected to said bottom section at opposite sides thereof along a portion of the curvature of the contour of the bottom section and extending in opposite direction from said point of connection, and cooperating means between said bottom and side wall forming strips to lock the side walls in a position at right angles to and following the contour of the bottom section.

9. A one-piece blank for a box body, comprising a bottom forming section of heart-shaped contour and opposite side wall forming strips each connected to said bottom section at opposite sides thereof along a portion of the curvature of the contour of the bottom section and extending in opposite direction from said point of connection, said strips being creased to fold upon themselves and provide a wall of double thickness and cooperating means between said bottom and side wall forming strips to lock the side walls in a position at right angles to and following the contour of the bottom section.

10. A one-piece blank for a box body, comprising a bottom forming section of heart-shaped contour and opposite side wall forming strips each connected to said bottom section at opposite sides thereof along a portion of the curvature of the contour of the bottom section and extend-

ing in opposite direction from said point of connection, and cooperating means between said bottom and side wall forming strips to lock the side walls in a position at right angles to and following the contour of the bottom section, said strips carrying segments to fold from the edge of the strips and extend beneath the bottom wall to reinforce the same.

11. A one-piece blank for a box body, comprising a bottom forming section of heart-shaped contour and opposite side wall forming strips at opposite sides thereof extending in opposite directions from a point along the curvature of the contour of the bottom section, said strips being creased to fold upon themselves and provide a wall of double thickness, and cooperating means between said bottom and side wall forming strips to lock the side walls in a position at right angles to and following the contour of the bottom section, said bottom section having portion creased along the straight sides thereof to be folded upwardly to provide flanges to cooperate with said side walls.

12. A one-piece blank for a box body, comprising a bottom forming section of heart-shaped contour and opposite side wall forming strips each connected to said bottom section at opposite sides thereof along a portion of the curvature of the contour of the bottom section and extending in opposite directions from said point of connection and with said strips extending substantially parallel to each other, and cooperating means between said bottom and side wall forming strips to lock the side walls in a position at right angles to and following the contour of the bottom section.

SAMUEL ROSEN.
